ABSTRACT

The labeling machine and method are for attaching brochures or similar materials to containers, such as bottles. The machine is provided with an improved container supporting member which automatically deposits a measured amount of glue or adhesive to an unlabeled portion of the container, so that a brochure or similar article may be placed in contact with said glue or adhesive and thereby attached to the container.

LABELING MACHINE

BACKGROUND OF THE INVENTION

In the past it has been customary to attach printed matter, other than labels, such as brochures, to labeled containers by use of cellophane tape, rubber bands, or the like. Although there are and have been available and in use a variety of labeling machines for attaching adhesive labels to containers, none of the machines are particularly well adapted to aid the attachment of the brochures or similar type articles to containers.

DETAILED DESCRIPTION OF THE INVENTION

The labeling machine of the present invention is provided with an improved container supporting mechanism. More specifically, it is provided with a container supporting mechanism which both supports the container so that an adhesive label can be attached thereto and also deposits glue or adhesive upon an unlabeled portion of said container so that a brochure can be attached to the container. In the preferred practice of the present invention, the supporting member is provided with glue or adhesive dispensing means which deposits a measured amount of glue or adhesive upon an unlabeled face of the container in response to the pressure exerted upon said container in the attaching of the label. In other words, in response to the label-attaching mechanism placing and securing a label on one face of the container, the improved supporting means deposits a measured amount of glue on another face of the container. A brochure or similar article can then be pressed into contact with said glue and thereby affixed to the container.

It is an object of the present invention to provide a simple, improved supporting member which can be employed with existing labeling machines to enable them to be used in the attachment of brochures or similar articles to containers.

It is a further object to provide an improved supporting member with glue-dispensing means which can be incorporated into conventional labeling machines with a minimum of structural modifications.

These and still further objects of the invention will be more fully understood from the description which follows.

In the drawings:

FIG. 1 is an elevational view of the supporting member of the present invention and a container.

FIG. 2 is an enlarged cross-sectional view of the glue-dispensing member of the supporting member.

In FIG. 1 of the drawing, a preferred embodiment of the invention is shown in which the unlabeled container 10 is positioned upon supporting member 11 which is provided with a glue-dispensing member 12. The glue-dispensing member 12 is connected to a pressurized container of glue (not shown) via the tube 13. The glue-dispensing member 12 is provided with a pressure responsive plunger 14 which extends above the uppermost surface of the supporting member 11, and an internal valve system (shown only in FIG. 2) which is opened by the downward movement of the plunger 14, such as that which occurs when pressure is exerted upon the container 10 in the process of labeling the container. When the plunger 14 is depressed the glue under pressure flows out of said dispensing member 12 unto that portion of the supported face of the container 11 immediately adjacent the plunger 14. When the label has been attached to the container and the downward force exerted upon the container by the labeling machine is withdrawn, the internal valve system closes and the glue no longer flows unto the container.

In FIG. 2 the internal valve system of the glue-dispensing member 12 can be seen. The glue-dispensing member 12 comprises a cylindrical member 15, which is closed at one end 16 and provided at the other end with an end wall 17 which is provided with a relatively large central aperture 18 and several small, peripherally located apertures 19. Located adjacent the closed wall 16 of cylindrical member 15 is a side inlet port 20 which communicates with the glue-transporting

tube 13. Positioned within the cylindrical member 15 and resting on inner surface of the closed wall 16 is the ball member 21. As shown in FIG. 2, the spring member 22 is partially compressed and positioned between the ball member 21 and the plunger member 14 which is positioned adjacent the end wall 17 of said cylindrical member 15.

As seen in FIG. 2, the plunger member 14 is provided with both a flangelike base member 23, which is circular in shape, and an upwardly extending elongated, plunger tip member 14a which is provided with a point 14b. The circular base member 23 is of slightly lesser diameter than the interior of the cylindrical member 15 but of sufficiently large diameter to completely close off the peripherally located apertures 19 in the end wall 17 from communication with the interior cavity 15 of the cylindrical member 15 when said base member is by the compressive force of the spring member 22 pressed into close contact with the inner surface of end wall 17. The upwardly extending elongated plunger tip member 14a is of only slightly lesser cross-sectional diameter than the central aperture 18, so that when the uppermost surface of the base 23 is in contact with the inner surface of end wall 17 the member 14a extends through the aperture 18 and above the outer surface of end wall 17.

When the plunger 14 is depressed, as shown in FIG. 2, the uppermost surface of the base member 23 is moved downwardly thus exposing the apertures 19, and the glue under pressure flows through the tube 13 into the internal cavity of the cylinder 15, around and about the ball 21, the spring 22, the flangelike base 23, and through the apertures 19 and onto that portion of the surface of the container 10 which is adjacent to and located about the plunger tip point 14b. Upon release of the force exerted upon the container and the plunger member 14, the spring 22 forces the elongated plunger tip member 14a upwardly through the central aperture 18 so that the uppermost surface of the base member 23 is against the inner end wall 17 and closes off the apertures 19 so that the flow of glue stops. The container 10, with a deposit of glue on its formerly supported face, is then removed, automatically or manually, and a brochure or similar article affixed to container by simply pressing it into contact with the deposit of glue. The glue or adhesive, which is preferably of the quick-drying type, secures the brochure to the container. The entire operation is then repeated.

In the preferred practice of the invention, the cylindrical member 15 is formed of two or more threaded pieces which can be both readily assembled to form an integral unit and disassembled for cleaning purposes.

The glue-dispensing member 12 preferably should be pressure responsive and yet sufficiently insensitive so that the weight of the container alone will not depress the plunger 14 and actuate the glue dispensing system. A variety of commercially available devices of the type which are commonly known as "spot tips" may be employed. Spot tips of the type described and shown in the drawings will operate satisfactorily at speeds up to 200 independent glue depositions per minute. Spot tips can be obtained which apply a ring, square or rectangular pattern of glue. Preferably, the spot tip is of the size which deposits a spot of glue one-half inch in diameter upon the container.

Any suitable free flowing, fast drying glue or adhesive may be employed. Preferably the glue is delivered to the glue-dispensing member under sufficient pressure to insure that an adequate amount of glue is deposited on the container on each depression of the plunger even when the plunger tip is depressed as often as 200 times a minute.

It will be obvious to those skilled in the art that the described improved supporting member may be employed with almost any type of labeling machine and may be used to deposit glue or adhesive upon a wide variety of various shaped containers, such as bottles, cans or cartons. It also will be readily apparent to those skilled in the art that a number of variations and changes may be made without departing from the spirit and scope of the present invention.

I claim:

1. A container-supporting member for a labeling machine which comprises a container-receiving member adapted to receive and support a container so that a label can be attached to one part thereof, said container-receiving member being provided with an automatic glue-dispensing means which is activated by a force greater than that exerted by the weight of the container to deposit glue upon a second part of the container.

2. A container-supporting member of claim 1 in which the glue-dispensing means comprises a pressure-activated support

5
10

tip.

3. A container-supporting member for a labeling machine which comprises a container-receiving member adapted to receive and support a container so that a label can be attached thereto, said container-receiving member being provided with an automatic glue-dispensing means which is so constructed so that it supports the weight of the container and is activated by a force greater than that exerted by the weight of the container to deposit glue upon the surface of said container.
